UNITED STATES PATENT OFFICE.

CYRUS KEHR, OF WINNETKA, ILLINOIS.

MEANS FOR RECORDING MOVING CARS.

SPECIFICATION forming part of Letters Patent No. 434,085, dated August 12, 1890.

Application filed November 16, 1889. Serial No. 330,565. (No model.)

To all whom it may concern:

Be it known that I, CYRUS KEHR, a citizen of the United States, residing at Winnetka, in the county of Cook and State of Illinois, have 5 invented certain new and useful Improvements in Systems for Recording Moving Cars; and I do hereby declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to a system by which the initials and numbers of moving cars may be recorded.

The object is to take the initials and numbers as the cars pass certain points—as, for 20 example, in leaving or entering a city, or in leaving or entering upon a new division of the railroad. It is intended by this means to form accurate information of the whereabouts of the cars of all grades used by the 25 railroads. The system is also designed to show the make-up of each passing train, the engine and all the cars being shown in the order which they occupy in the train. At present some railroad companies station a 30 man at a point where all trains of that division necessarily pass. The duty of this man is to note on paper by hand the initials and numbers of as many cars as he is able to take while the trains pass. Experience has 35 shown that this man can take only a portion of the passing cars, and is always liable to error in writing the numbers and initials. Moreover, he can only work where there is sufficient light to read the initials and numbers 40 on the cars. While a train moves rapidly he is unable to record any considerable portion of the train. The system which I have devised is designed to operate automatically, or almost wholly so, and make an impression of the initials and numbers of all 45 cars and engines upon a suitable surface.

In the accompanying drawings, Figure 1 is a side elevation of three cars joined as in a train. Fig. 2 shows a car in transverse section and shows a side elevation of the apparatus for taking the impression. Fig. 3 shows

one of the number-plates. Fig. 4 is a horizontal section illustrating the apparatus for taking the impression. Fig. 5 is a vertical section in line $\alpha\alpha$ of Fig. 4, the portion of 55 the car to which the number-plate is attached being shown.

In said drawings, A A are the cars.

B is a number-plate. This bears the number or initials of the car, as indicated in Fig. 60 3. These numbers may be formed in relief-like type, with broad faces for making an impression by means of coloring-matter, or they may be in relief with sharp outlines for making an indentation in a suitable surface on 65 the recording apparatus, or they may be depressed so that the surface around them will print in color, or fitted to the apparatus to mold the letters and figures in relief on a suitable plastic surface controlled by the recording apparatus. These plates are to be arranged upon the cars at the same vertical and lateral distance from the rail R and below or outside of any other portions of the car which might interfere with the recording 70 75 apparatus. The drawings show these plates arranged below the outer side of the car with the face bearing the numbers directed inward.

C is a roller so supported from the ground 80 as to reach up against the bottom of each plate B as it passes by. This roller may itself have a yielding surface to receive indentations from each number-plate, so that after the train has passed its cars will be registered 85 upon the surface of said roller, or a band, as C', may be placed around said roller for each train and receive the impressions of the number-plates as the train passes. It is obvious 90 that if the train moves in the direction of the arrow in Fig. 5 the roller will be turned by the moving plate B, so that each plate will make its impression upon a separate portion of the surface of the roller or the band applied to such roller; and it is also obvious 95 that the impressions of the different cars will stand upon the roller or the band in the order occupied by the cars in the train. The roller C is preferably mounted on an ordinary yielding support, in order that it may accommodate itself in a vertical direction to the variations in the height of the plates on the dif- 100

ferent cars due to swaying or unequal loads. This is accomplished by the apparatus shown in Figs. 4 and 5.

D is a horizontal rock-shaft arranged at right angles to the railroad-track and supported in bearings D' D². At the end nearest the track said rock-shaft is provided with a laterally-directed arm D³, at the outer end of which is a spindle D⁴, extending through the axis of the roller C. At its end farthest from the track said rock-shaft may have a horizontal lateral arm D⁵, extending in the direction opposite the arm D³, and a weight D⁶, applied to the free end of said arm D⁵, will counterbalance the roller C and hold it up in the path of the plates B. The roller C may also be held up in the path of the plates B by means of a coiled spring D⁷, secured to the rock-shaft at d⁷ and some fixed portion of the apparatus, as d⁸. The tension of this spring should be such as to hold the roller C up at the desired elevation, but allow the latter to yield somewhat as the plate B passes over it. A ratchet-wheel c may be applied to the side and around the axis of the roller C, and provided with a pawl c', mounted upon the arm D³. The function of said ratchet-wheel and pawl is to prevent the recoiling or reverse movement of the roller C. It will be seen that the roller C may also be supported in a yielding manner by being mounted in vertical guides and a suitable application of springs and weights. The impression of the number-plates B may also be made upon a long ribbon of paper or a woven fabric by means of coloring-matter—as, for example, ink or the carbon of what is known as "carbon-paper."

E is a roller mounted upon the free end of the rock-shaft D, nearest the track, and upon this may be wound a long paper or ribbon E'. This ribbon may be held over the upper surface of the roller C, so as to come into contact with the plates B. As these plates pass, they engage the ribbon and the roller and make an impression upon said ribbon. The roller E may be mounted elsewhere than on the rock-shaft D. Two such rollers may be used—one for the paper ribbon E' and the other for a ribbon bearing color; or the paper and the color ribbons may be wound together upon the same roller. Several ribbons may be used, when desired, so that the record is produced in manifold, a copy being made, for example, for the general superintendent, general freight agent, division superintendent, division freight agent, division passenger agent, and the car accountant.

The apparatus may be arranged to operate automatically for a considerable time without an attendant, or the attendant may be present to insure the accurate operation of the apparatus, and to remove from the apparatus the record of each train as soon as made.

65 The apparatus may be provided with supporting-wheels F, and mounted upon a track

G, arranged at right angles to the rails R, on which the cars A A move. Upon this track G the apparatus may be moved back and forth by the attendant, as may be required in its care and operation. At its end toward the rail R the track G should have a stop G', to limit the movement of the apparatus toward the moving cars, said stop being so located as to allow the roller C to move toward the car until it rests under the number-plate and no farther. By this means it may be made impossible for the apparatus to come into contact with the trucks of the car. Where trains pass frequently it may be desirable to have two sets of the apparatus, so that one may stand in position for recording while the other is being supplied with new rolls or ribbons.

The apparatus may also be arranged to slide on the way G instead of rolling by means of wheels F. The roller C may also be withdrawn from the path of the number-plates by drawing the rock-shaft D, through the bearings D' and D², away from the cars or track. For this purpose the shaft D may be without shoulders at said bearings. It will be seen that if the spring D⁷ is used, as shown in Fig. 4, the shaft may be drawn away from the track, the spring D⁷ being compressed to permit the movement of said shaft. In this case the spring may also serve to return the roller C to its limit toward the track.

Numerous features necessarily mentioned, but which cannot be claimed herein, will be made the subject-matter of other applications for Letters Patent.

I claim as my invention—

1. In a system for recording moving cars, number-plates applied to the cars at a chosen distance and direction from one of the rails of the railroad-track, and a yielding roller suitably located to make contact with said number-plates and take impressions from said number-plates, substantially as shown and described.

2. In a system for recording moving cars, number-plates applied to the cars at a chosen distance from the track, a yielding roller arranged to make contact with said number-plates, and a roller for receiving a ribbon to pass over said yielding roller and receive impressions from the number-plates, substantially as shown and described.

3. In a system for recording moving cars, number-plates applied to the cars at a chosen distance from the track, a yielding roller arranged to make contact with said number-plates, a band bearing coloring-matter extending over the surface of said yielding roller, and a roller for receiving a band to extend over said yielding roller and receive colored impressions as the number-plates pass over said roller and said bands, substantially as shown and described.

4. In a system for recording moving cars, number-plates applied to the cars at a chosen

distance from the track, a yielding roller arranged to make contact with the number-plates and provided with means for preventing its recoil or reverse movement, substantially as shown and described.

5. In a system for recording moving cars, number-plates applied to one of the cars at a chosen distance from the track, a yielding roller mounted in a way at right angles to the 10 track upon which the cars move, whereby said roller may be shifted at right angles to said track into or out of the path of said number-plates, substantially as shown and described.

6. In a system for recording moving cars, 15 number-plates applied to the car at a chosen distance from the track, a rock-shaft suitably mounted and having a laterally-directed arm, a roller C, mounted upon said laterally-directed arm, and a spring or its equivalent for 20 holding said shaft and arm in such position as to bring said roller into the path of said number-plates, substantially as shown and described.

7. In a system for recording moving cars, 25 number-plates applied to the cars at a chosen distance from the track, a suitably-mounted rock-shaft D, a spring D⁷ or its equivalent applied to said rock-shaft to hold it in a chosen position, an arm D³, extending laterally from 30 said rock-shaft, a spindle D⁴, extending from said arm in a direction parallel to said rock-shaft, a roller C, mounted upon said spindle

D⁴ and extending into the path of said number-plates, substantially as shown and described.

8. In a system for recording moving cars, 35 number-plates applied to said cars at a chosen distance from the track, a suitably-mounted rock-shaft D, a spring D⁷, an arm D³, extending laterally from said shaft D, a spindle D⁴, extending from said arm D³ in a direction 40 parallel to said rock-shaft, a roller C, mounted upon said spindle D⁴ and extending into the path of said number-plates, a ratchet-wheel c, joined to said roller C, and a pawl c', mounted upon said arm D³ and arranged to 45 engage said ratchet-wheel c, substantially as shown and described.

9. In a system for recording moving cars, 50 number-plates applied to the cars at a chosen distance from the track, a rock-shaft D, a spring D⁷, a roller axially in line with said rock-shaft, and a roller C, supported upon an arm extending laterally from said shaft D and extending into the path of said number-plates, said rollers being in the same plane 55 at right angles to said rock-shaft, substantially as shown and described.

In testimony whereof I affix my signature, in presence of two witnesses, this 13th day of November, in the year 1889.

CYRUS KEHR.
